2 SHEETS-SHEET 2.

FIG. II.

UNITED STATES PATENT OFFICE.

JAMES H. MOTT, OF BATTLE CREEK, MICHIGAN.

STRAW-SPREADER.

1,078,800.

Specification of Letters Patent. Patented Nov. 18, 1913.

Application filed December 10, 1912. Serial No. 735,893.

To all whom it may concern:

Be it known that I, JAMES H. MOTT, a citizen of the United States, residing at 186 Champion street, Battle Creek, Michigan, have invented certain new and useful Improvements in Straw-Spreaders, of which the following is a specification.

This invention relates to improvements in straw spreaders.

10 The main objects of this invention are: First, to provide an improved straw spreader adapted as an attachment to an ordinary farm wagon or the like, which may be quickly connected or disconnected 15 from the wagon without changing or modifying the wagon other than to provide a suitable draft coupling or connection for the spreader attachment. Second, to provide an improved straw spreader adapted 20 as an attachment, which is of very large capacity. Third, to provide an improved straw spreader having these advantages, which is simple and economical in structure and one which is durable and not likely 25 to get out of repair.

Further objects and objects relating to structural details, will definitely appear from the detailed description to follow.

I accomplish the objects of my invention 30 by the devices and means described in the following specification.

The invention is clearly defined and pointed out in the claims.

A structure which is a preferred embodiment of my invention is clearly illustrated 35 in the accompanying drawing forming a part of this specification, in which:

Figure I is a detail side elevation of a structure embodying the features of my invention, the same being shown in operative relation to a wagon. Fig. II is a plan view 40 of my improved spreader, one of the wheels being broken away. Fig. III is a detail vertical section on a line corresponding to line 3—3 of Fig. I. Fig. IV is a detail horizontal section on a line corresponding to line 4—4 of Fig. I. Fig. V is an enlarged detail vertical section on a line corresponding to line 5—5 of Fig. IV.

50 In the drawing similar reference characters refer to similar parts throughout the several views, and the sectional views are taken looking in the direction of the little arrows at the ends of the section lines.

55 Referring to the drawing, the carrying

and driving wheels 1 are secured to the axle 2 so that the axle is driven thereby. The frame is mounted on brackets 3 provided with suitable bearings for the axle 2. The frame in the structure illustrated consists of cross pieces or sills 4—4 mounted on the brackets 3, the cross piece or sill 9 and the longitudinal sills 5 secured to these cross pieces to provide a rigid frame. A supporting bracket 10 for the cross sill 9 is 60 carried by the draft bar 11. The draft bar 11 is provided with diverging braces 13 provided with suitable bearings 40 for the axle. Collars 41 engage these bearings 40 and prevent longitudinal movement of the axle. 65 The draft bar 11 is provided with a draft hook 14 at its forward end adapted to be engaged with a suitable coupling as the clevis 16 on the reach 15 of a wagon. The forward end of the spreader frame is, by 70 this connection, supported under the wagon body or rack 17, as shown in Fig. I. On the axle 2 is a driving sprocket 18. The sprocket is connected to the axle by means of the clutch 19. The means for shifting 75 this clutch into and out of operative position are not illustrated as they will be readily understood. A shaft 22 is supported above the axle by the bearings 22' mounted on the under side of the longitudinal sills 5. The shaft 22 is connected to the driving 80 sprocket 18 by the sprocket chain 20 and the sprocket 21 on the shaft 22. The conveyer apron 29 is supported at the front end of the frame by means of suitable rollers 30 and 42. The roller 30 is supported by the brackets 31 so that the front end of the conveyer is under the rear end of the wagon rack when the spreader is attached or coupled to a wagon. The roller 42 is 85 supported by bearing pedestals 28 mounted on the outer longitudinal sills 5. The pedestals or brackets 28 are considerably higher than the brackets 31 so that the carrier is supported in a forwardly inclined position, 90 with the rear end considerably elevated. The carrier or conveyer 29 is driven by the sprocket chain 24 which is arranged on the sprocket wheel 23 on the driven shaft 22 and the idler 25 by which it is supported 95 in driving engagement with the sprocket wheel 27 on the roller 42. The idler 25 is carried by the adjustable bracket 26 having an arm pivotally mounted on one of the pedestals 28. The bracket 26 is adjustably 100

supported by the bolt 43 engaging a slot 44 in the bracket. The driven shaft 22 is pivotally provided with a balance wheel 32.

The vertically disposed fork shafts 34 are supported by bearings 35 carried by the cross bars 7 secured to blocks 8 on the frame. The shafts 34 are connected by the beveled gears 32 and 33 to the driven shaft 22. The beveled gears 32 are mounted on the shaft 22 to mesh with the beveled gears or pinions 33 on the fork shafts 34. The shafts 34 are provided with fork arms 36 provided with spring forks 38 at their ends. Each shaft 34 in the structure illustrated is provided with a pair of the arms, one disposed transversely of the other. These arms are spaced so that the lower arm is below the horizontal plane of the rear end of the conveyer 29, while the upper arm is above such plane. These spring forks 38 are mounted on pins 39 arranged through the bars, the forks being substantially such as are employed in hay tedders. The conveyer delivers straw to these spreader forks rapidly. For convenience in mounting the bars or arms 36 upon the vertical shafts, the shafts are provided with arm attaching plates 37.

In use, the spreader is coupled to the wagon to be unloaded and the straw pitched or otherwise delivered to the carrier 29 by which it is delivered to the spreader forks which throw the straw to the rear and to each side. The spreader members are driven in opposite direction through the connections described. The rear end of the carrier or conveyer being elevated, the straw is effectively delivered to the spreader forks so that the spreader forks strike into the same in such a manner that it is effectively discharged or thrown from the spreader and torn to pieces and very evenly distributed.

There is little likelihood of the structure clogging and it is adapted for spreading both dry and wet straw evenly and rapidly. The structure being readily attached to or detached from a wagon, may be successively connected with different wagons. This is of decided advantage in drawing straw from a threshing machine or the like as the spreader may be used in unloading one wagon while the other is being loaded.

The spreader may be coupled and uncoupled very quickly and easily as will be readily understood. While I prefer to employ the reach as a coupling and draft member for the spreader as it is only necessary to add a clevis or other draft loop to receive the draft hook 14 in order to enable the adjustment of the spreader, other coupling means may be provided.

I have illustrated and described my improvements in a simple and practical embodiment. I have not attempted to illustrate or describe various modifications which

I contemplate as I believe the structure illustrated will enable those skilled in the art to which this invention relates to embody the same as conditions may require. I desire, however, to be understood as claiming my improvements specifically in the form illustrated as well as broadly within the scope of the appended claims.

Having thus described my invention, what I claim is new and desire to secure by Letters Patent is:

1. In a straw spreader, the combination with a frame of carrying and driving wheels, an axle driven thereby, frame supports having bearings for said axle, a draft bar provided with a bearing for said axle, the front end of said frame being mounted on said draft bar, a conveyer mounted on said frame, a pair of fork shafts disposed in a vertical position at the rear of said conveyer, a driven shaft mounted on said frame above said axle and below said fork shafts, driving connections for said fork shaft and driven shaft, and driving connections from said driven shaft to said conveyer.

2. In a straw spreader, the combination with a frame, of carrying and driving wheels, an axle driven thereby, the rear end of said frame being mounted on said axle, a draft bar provided with bearings for said axle, the forward end of said frame being mounted on said draft bar, a conveyer mounted on said frame, a pair of vertically disposed fork shafts having arms thereon provided with forks at their ends, a driven shaft mounted on said frame above said axle, driving connections from said driven shaft to said axle, gears connecting said fork shafts to said driven shaft, and driving connections from said driven shaft to said conveyer.

3. In a straw spreader, the combination with the carrying and driving wheels, of an axle driven thereby, a frame mounted on said axle, a draft bar provided with bearings for said axle, the forward end of said frame being mounted on said draft bar, a conveyer mounted on said frame, shafts disposed vertically at the rear of said conveyer having arms thereon provided with forks disposed to coact with said conveyer and act on the straw above and below the same, and driving connections for said conveyer and shafts to said axle.

4. In a straw spreader, the combination with a frame, carrying and driving wheels, a driven axle, a conveyer arranged on said frame in a forwardly inclined position, spreading forks mounted for rotation in horizontal planes at the rear of said conveyer, part of the forks rotating in planes above and a part rotating in planes below the horizontal plane of the rear end of said conveyer, driving connections from said axle to said conveyer and said spreading forks,

a draft bar, and means for coupling said draft bar to the rear end of the reach of a wagon whereby the forward end of said conveyer is supported under the rear end of the

5 wagon body.

5. In a straw spreader, the combination with the carrying and driving wheels, of an axle driven thereby, a frame mounted on said axle, a draft bar provided with bearings 10 for said axle, the forward end of said frame being mounted on said draft bar, a conveyer mounted on said frame, shafts disposed vertically at the rear of said conveyer hav-

ing arms thereon provided with forks disposed to coat with said conveyer and act on the straw above and below the same, and driving connections for said conveyer and shafts.

In witness whereof, I have hereunto set my hand and seal in the presence of two witnesses.

JAMES H. MOTT. [L.S.]
